[57] CLAIM

The ornamental design for a casing for a knife block, as shown and described.

DESCRIPTION

FIG. 1 is a front-right-top perspective view of a casing for a knife block, showing our new design;
FIG. 2 is a front elevational view thereof;
FIG. 3 is a rear elevational view thereof;
FIG. 4 is a left elevational view thereof;
FIG. 5 is a right elevational view thereof;
FIG. 6 is a top plan view thereof;
FIG. 7 is a bottom plan view thereof;
FIG. 8 is a front-right-top perspective view of a working embodiment of our new design, the knife block is shown in broken lines for illustrative purposes only; and,
FIG. 9 is a front-right-top perspective view of a working embodiment of our new design, the knife block and a plurality of knives, spoons and a pair of scissors disposed therein are shown in broken lines for illustrative purposes only.
